[57] CLAIM

The ornamental design for a recessed wall lamp, as shown and described.

DESCRIPTION

FIG. 1 is a bottom plan view of the recessed wall lamp showing my new design;

FIG. 2 is a top plan view thereof;

FIG. 3 is a side view thereof;

FIG. 4 is an end view thereof; and,

FIG. 5 is an exploded perspective view thereof.

The opposite side and end of the recessed wall lamp are identical to the side and end shown in FIGS. 3 and 4.

FIG. 1

FIG. 2

FIG. 3

FIG. 4
